United States Patent Office

Des. 230,125
Patented Jan. 29, 1974

230,125

KNIFE

Donald Wallace, Croton-on-Hudson, N.Y., assignor to
H. E. Lauffer Co., Inc., Somerset, N.J.

Filed July 25, 1972, Ser. No. 274,920

Term of patent 14 years

Int. Cl. D7—03

U.S. Cl. D7—137

FIG. 1. FIG. 2. FIG. 3. FIG. 4.

FIG. 1 is a top view of a knife showing my new design;

FIGS. 2 and 4 are side views of the knife of FIG. 1;

FIG. 3 is a bottom view thereof;

FIG. 5 is an end view thereof looking in the direction from the tip of the blade portion toward the handle;

FIG. 6 is a rear end view of the knife looking in the direction from the handle toward the blade portion thereof;

FIG. 7 is a sectional view thereof taken on line 7—7 of FIG. 1; and

FIG. 8 is a sectional view thereof taken on line 8—8 of FIG. 1.

I claim:

The ornamental design for a knife, as shown.
